CURRENT-LIMITING FUSE

William S. Edsall, Boston, Mass., Kenneth W. Swain, Hampton Falls, N. H., and Frederick J. Kozacka, Amesbury, Mass., assignors to The Chase-Shawmut Company, Newburyport, Mass., a corporation of Massachusetts

Application October 4, 1949, Serial No. 119,476

42 Claims. (Cl. 200—120)

1

The invention refers to fuses of the current-limiting type which, when subjected to an A.-C. fault current of short-circuit current proportions, effect interruption of the circuit in less, or even substantially less, than half a cycle of the current wave. Such fuses, when subjected to a D.-C. short-circuit current having a similar rate of rise as an A.-C. short-circuit current, effect interruption of the D.-C. current in a similarly short period of time as in the case of A.-C. current interruption. The principal object of the invention is to provide a low voltage current-limiting high current interrupting capacity fuse which is improved in every respect compared to fuses of the same general type which were known heretofore.

Current-limiting fuses are called to interrupt fault currents of short-circuit current proportions before the currents reach the maximum short-circuit current strength which the system or circuit with which the fuses are associated is capable of producing. That current is generally referred to as the available short-circuit current. The maximum current which is allowed to flow through a circuit which is protected by a current-limiting fuse is called the let-through current. Obviously, the let-through current is much smaller than the available short-circuit current. Any current exceeding the let-through current is considered a short-circuit current.

Current-limiting fuses are often also required to interrupt overload currents of much smaller proportions than short-circuit currents if the overload currents are of relatively long duration. Small overload currents which a current-limiting fuse may be required to interrupt may be in the order of eight to ten times the rated current of the fuse.

Originally, low voltage current-limiting fuses were relatively compact on account of the high heat dissipating ability of their pulverulent filler and on account of the fact that the arc energy $\int i^2 \cdot r \cdot dt$ which is dissipated in them is relatively small in comparison to the arc energy dissipated in any other circuit interrupting device. Increasing concentration of loads made it necessary to provide current-limiting fuses of increased current carrying and interrupting capacity rating and the size and bulk of such current-limiting fuses has tended to increase in proportion to their current carrying and interrupting capacity rating. Fuses for circuits capable of producing short-circuit currents in the order of several hundred thousand amperes are extremely bulky and difficult to accommodate where space limitations are of a serious nature. It is, therefore, an object of the invention to provide a low voltage current-limiting high current interrupting capacity fuse which is smaller and more compact than prior art current-limiting fuses of a similar rating.

The size and bulk of a current-limiting fuse

2

depend primarily upon the amount of arc energy $\int i^2 \cdot r \cdot dt$ which is dissipated in the fuse. It was believed, heretofore, that the known designs of current-limiting fuses achieve the aim of minimizing the amount of arc energy which must necessarily be dissipated about as well as that aim can possibly be achieved. It was found, however, that it is possible to effect a drastic decrease in the amount of arc energy compared to the amount of arc energy which is dissipated in current-limiting fuses of known design. In accordance with this invention, a fuse is provided the size and bulk of which are reduced in accordance with the newly discovered possibility of further reduction of arc energy.

One of the major difficulties involved in the design of current-limiting fuses is their tendency to behave differently depending upon whether the current under interruption is relatively high or small. A current-limiting fuse is required to achieve consistently sufficiently rapid interruption irrespective of whether the current under interruption is relatively high or small. It is, therefore, another object of this invention to provide a current-limiting fuse which operates satisfactorily both on the occurrence of fault currents of short-circuit current proportions and of relatively small overload currents of inadmissible duration.

It has been found that the voltage gradient in a current-limiting fuse is in the order of 300 volts per centimeter at the instant of arc initiation and that the voltage gradient at the point of arc initiation decreases rapidly with increasing arcing time. Because of this decrease of the voltage gradient at the point of arc initiation, the rate of rise of the total arc voltage—due to progressive growth of the length of the arc gap on account of continued arcing—will be greatly reduced if the arcing time is not relatively short. It is, therefore, another object of this invention to provide a current-limiting fuse in which the arc voltage rises so rapidly in case of interruption of relatively small overload currents that final arc extinction is effected before the voltage gradient at the point of arc initiation drops considerably.

Current-limiting fuses which are made according to this invention comprise a fuse link which is arranged in a casing and interconnects terminal elements on opposite ends of the casing. The link has a plurality of portions of reduced cross-section spaced substantially equidistantly along substantially the entire length of the link and a plurality of portions of relatively larger cross-section intermediate the reduced cross-section portions. The reduced cross-section portions have a sufficiently small cross-sectional area to initiate arcing at instantaneous currents far below the available short-circuit current of the circuit or the system with which the fuse is associated. The reduced cross-section portions of the link are very short and the length of the portions

of relatively larger cross-section is a multiple of the length of the reduced cross-section portions. The fuse comprises further a pulverulent arc-extinguishing substance of predetermined arc-extinguishing capacity filled into the casing and surrounding the link substantially throughout the total length thereof. The substance or filler has a sufficiently high arc-extinguishing capacity in relation to the arcs which are formed at said portions of reduced cross-section to effect complete interruption of any short-circuit current that the circuit with which the fuse is associated is capable of producing in less than $\frac{1}{120}$ of a second after fault inception, i. e. less than half a cycle of a 60 cycle current wave. The total length of said reduced cross-section portions and of said relatively larger cross-section portions exceeds the length of the link vaporized under the most onerous circuit interrupting conditions to which the fuse may be subjected in the circuit with which it is associated.

Interruption of the short-circuit current by means of such a fuse is initiated by fusing of the link at the small cross-section portions. At the end of the interrupting process, the small cross-section portions are entirely and the large cross-section portions partially, but not entirely, vaporized, not even under the most onerous circuit interrupting conditions to which the fuse may be subjected. Such a fuse consists, after blowing, of a series of spaced bodies of melted sand or fulgurites and intermediate metallic remainders of the link. These remainders of the link are sometimes formed by a more or less solid piece of metal substantially in its original state with its length reduced by arcing and sometimes by a pattern of coarsely dispersed metal pieces.

It is well known in the art to provide fuse links of low voltage fuses with portions of reduced cross-section alternating with portions of relatively larger cross-section. In a certain type of fuses comprising such links the large cross-section portions, because of their large heat capacity, tend to delay the interruption of the circuit by the fuse in case of protracted relatively small overload currents. The relatively large cross-section portions of the link are not involved in the interruption of large currents in the nature of short-circuit currents. The latter is effected at the portions of reduced cross-section only. Obviously, the present invention has no direct relation to the prior art time-lag fuses of the aforementioned type.

It is also well known in the art to provide the links or fusible elements of high voltage fuses with a plurality of portions of reduced cross-section alternating with portions of relatively larger cross-section. These prior art fuses are not of the current-limiting type and the plurality of portions of reduced cross-section of their links is intended to provide a multibreak feature. As a general rule low voltage fuses do not call for a multibreak feature. The link of a current-limiting fuse is vaporized on the occurrence of a fault current of short-circuit current proportions substantially simultaneously at any point along the entire length of the link, resulting in insertion of arc resistance into the circuit at a more rapid rate than can be achieved in any prior art high voltage multibreak fuse. In a conventional current-limiting low voltage fuse, on the occurrence of a short-circuit current a striation phenomenon occurs throughout the entire length of the link, resulting in the formation of multibreaks, though the cross-section of the link is uniform through-

out its entire length. This is an automatic multibreak feature inherent in current-limiting fuses.

It is also known in the art to provide the fuse links of high voltage current-limiting fuses with portions of reduced cross-section. The purpose of the portions of reduced cross-section in the links of these fuses is to cause progressive insertion of arc resistance into the circuit during the entire arcing time to keep the rate of change of current

$$\frac{di}{dt}$$

as constant as possible. This, in turn, tends to limit the inductive surge voltages which may occur in inductive high-voltage circuits when a current-limiting fuse is caused to blow and which may present a serious danger to circuit insulation. In low voltage circuits the danger resulting from inductive surge voltages is much less serious than in high voltage circuits and can effectively be eliminated by arranging a plurality of fuse links in parallel in the circuit which fuse links melt and vaporize sequentially under the action of fault currents of short-circuit current portions. Hence inductive surge voltage control is no reason for providing the links of current-limiting low voltage fuses with a plurality of portions of reduced cross-section. Though control of inductive surge voltages and the objects of this invention may both be achieved by means of links having a plurality of portions of reduced cross-section alternating with large cross-section portions, either case calls for different geometrical link configuration. A link having a plurality of reduced cross-section portions designed for inductive surge voltage control will not achieve the objects of the present invention. Vice versa, a link having a plurality of reduced cross-section portions designed to achieve the objects of the present invention will not achieve inductive surge voltage control. Inductive surge voltage control requires progressive insertion of arc resistance into the circuit. To achieve the objects of this invention, the length of the reduced cross-section portions ought to be very short in comparison to the length of the large cross-section portions. Melting and vaporization of the former under the action of a fault current of short-circuit current proportions results in insertion of but little arc resistance into the circuit. The subsequent melting and vaporization of the latter results in sudden insertion of a large amount of arc resistance into the circuit, which is clearly the opposite of what is required for inductive surge voltage control.

Both the portions of relatively small cross-section and the intermediate portions of relatively large cross-section of links of prior art high-voltage current-limiting fuses are designed to be completely vaporized at all interruptions of a relatively onerous kind, whereas the large cross-section portions of the link of a fuse embodying the present invention are designed not to be completely vaporized under the most onerous circuit interrupting conditions to which the fuse may be subjected in the circuit with which it is associated. The significance of this relative excess of link length or link metal will now be explained.

In fuses embodying the present invention the function of the small cross-section portions and of the large cross-section portions of the link varies depending upon the magnitude of the current under interruption.

Currents in the nature of short-circuit currents rise at a very rapid rate and reach high magnitudes, unless previously interrupted. In fuses embodying the present invention, on occurrence of a short-circuit or like fault, the reduced cross-section portions of the link reach their fusing temperature virtually instantly which limits the let-through current to an unusually low value. The adjacent intermediate large cross-section portions of the link are still cool at the time the interrupting process is initiated at the small cross-section portions. Therefore, the large cross-section portions are capable of absorbing large amounts of heat during the subsequent phase of the interrupting process during which they are partially vaporized.

Currents in the nature of relatively small protracted overloads result in a relatively slow rise of the temperature of the reduced cross-section portions of the link. The rate of rise of the temperature of the reduced cross-section portions is particularly small on account of the shortness of their length relative to the length of the large cross-section portions. The heat flow from the reduced cross-section portions to the large cross-section portions of the link extending over a considerable period of time prior to initiation of the interrupting process results in a more even temperature distribution along the entire length of the link than in any prior art low voltage current-limiting fuse. Because of that even pre-heating of the entire link before the time of arc initiation, a smaller amount of arc energy needs to be dissipated for producing the gap required for effecting complete interruption of the circuit than is required without such an even pre-heating of the entire link length.

In the accompanying drawings:

Fig. 1 is a longitudinal cross-sectional view of a fuse embodying the present invention;

Fig. 2 is a cross-sectional view along line A—A of Fig. 1;

Fig. 3 is a diagram illustrating the decrease with arcing time of the voltage gradient at the point of arc initiation;

Fig. 4 is a diagram illustrating the behavior of prior art current-limiting fuses and of current-limiting fuses of the present invention under short-circuit conditions;

Fig. 5 is a longitudinal cross-sectional view of a modification of the structure shown in Figs. 1 and 2;

Fig. 6 shows, in cross-section, a structure similar to that shown in Fig. 5, however, having a smaller interrupting capacity rating;

Fig. 7 shows, in cross-section, a modification of the structure shown in Fig. 6 particularly designed to effect rapid interruption of a circuit after a long time delay in case of relatively small overloads;

Fig. 8 is a cross-sectional view on a larger scale along B—B of Fig. 7;

Fig. 9 is a longitudinal cross-sectional view of a current-limiting fuse having a filler designed to evolve a controlled, limited amount of gas;

Fig. 10 shows in front elevation and partially in cross-section a composite fuse having a very high current-carrying capacity intended for use in circuits having very high available short-circuit currents; and

Fig. 11 is a cross-sectional view along C—C of Fig. 10.

In all figures the same reference signs are applied to like parts.

Referring now to Figs. 1 and 2, reference numerals 1 and 2 are applied to the terminal elements or caps arranged on opposite ends of casing 3. The fuse link 4 interconnects the terminal elements 1 and 2 and may be spot welded to them. The terminal elements 1 and 2 and the fuse link 4 are inserted in an electric circuit having a circuit voltage not exceeding 600 volts. This is the voltage range for which the fuses according to the present invention are primarily intended. The circuit into which the fuse is inserted has been indicated diagrammatically in Fig. 1 by conductors 5a and 5b. The fuse shown in Figs. 1 and 2 lends itself for use in A.-C. circuits as well as in D.-C. circuits, as will be more fully explained below. The fuse link 4 has a plurality of portions 4a of reduced cross-section spaced substantially equidistantly along substantially the entire length of link 4 and a plurality of portions 4b of relatively larger cross-section intermediate said reduced cross-section portions. Each reduced cross-section portion 4a has a sufficiently small cross-sectional area to melt and to initiate arcing at instantaneous current intensities far below the available short-circuit current of the circuit into which the fuse is inserted. The available short-circuit current of the circuit into which the fuse is inserted may, for instance, be in the order of 10³ peak amperes and arcing may be initiated at an instantaneous current intensity of 1 peak amperes, or 10% of the available short-circuit current. Each relatively larger cross-section portion 4b has a length which is a multiple of the length of the reduced cross-section portions 4a. The casing 3 is filled with a pulverulent arc-extinguishing filler 6, e. g. clean quartz sand, surrounding fuse link 4. The filler 6 has a sufficiently high arc-extinguishing capacity in relation to the number of points of arc initiation—which is obviously the same as the number of portions 4a of reduced cross-section—to effect extinction of any short-circuit arc that the circuit into which the fuse is inserted is capable of producing in less than $\frac{1}{120}$ of a second after the time of fault inception. In other words, if the fuse is inserted into an A.-C. circuit having a frequency of 60 cycles per second, the time during which a short-circuit current is permitted to rise plus the arcing time will be less than half a cycle. If the fuse is designed to interrupt the circuit with a minimum of arc energy, the time during which the short-circuit current is permitted to rise plus the arcing time will be much less than half a cycle of the current wave. A fuse according to the present invention, when interrupting a short-circuit current in a D.-C. circuit, will have an arcing time and dissipate an amount of arc energy comparable to the A.-C. case provided that all other conditions are similar. The total length of the reduced cross-section portions 4a and of the relatively larger cross-section portions 4b exceeds the length of link 4 which is vaporized under the most onerous circuit interrupting conditions to which the fuse may be subjected in the circuit into which it is inserted. Hence, the fuse link 4 will never be entirely vaporized by arcing. The portions of the link which will not be vaporized even under the most onerous circuit interrupting conditions, i. e. when the amount of arc energy is an optimum, has been indicated in all figures by cross-hatching. The cross-hatched portions of the link may either retain their complete

integrity after the fuse has blown, or they may be broken up into a plurality of separated metal parts. However this may be, the appearance of the cross-hatched portions of the link after the fuse has blown is very different from the appearance of the other portions thereof since the cross-hatched portions retain substantially their metallic nature while the other portions are converted into fulgurites which are in the nature of glass rather than that of a metal.

The required number of portions 4a of reduced cross-section and the total length of the reduced cross-section portions 4a and of the relatively larger cross-section portions 4b depends upon such factors as the circuit voltage, the available short-circuit current and its rate of rise, the ratio between the cross-sectional area of the reduced cross-section portions 4a and the relatively large cross-section portions 4b, the metal of which link 4 is made, the arc-extinguishing capacity of filler 6, the pressure prevailing within casing 3 during interruption, etc. Correct data for the required number of reduced cross-section portions 4a and for the total length of the reduced cross-section portions 4a and of the relatively larger cross-section portions 4b can readily be determined by power laboratory tests. Such tests can be greatly simplified by subjecting sets of experimental fuse structures of the type shown in Figs. 1 and 2 to various interrupting conditions and observing in a radioscope the pattern resulting from blowing of the fuses. If that pattern approaches that indicated in Fig. 1, i. e. comprises a number of fulgurites resulting from vaporization of portions of the link and melting of the surrounding pulverulent filler alternating with more or less metallic portions, this is an indication that the fuse is proportioned substantially in accordance with the teachings of the present invention. After having found a relatively rough approximation to the required proportions, proportions assuring optimum effectiveness of the fuse structure may be determined by continued testing of varying structures along the established lines.

A point to consider in proportioning a fuse according to the present invention may be the inductive voltage surge that is permissible in a particular circuit. On the basis of a given limitation of the permissible inductive voltage surge, the number x of portions 4a of restricted cross-section may be determined as follows:

Let r be the total arc resistance of a given fuse and r_x the arc resistance developed at each point of reduced cross-section of the fuse link. Then

$$x = \frac{r}{r_x} \quad (1)$$

Assuming the fuse is placed in a D.-C. circuit whose circuit voltage is E volts and whose inductance is L henries. The voltage equation for such a circuit is

$$L \frac{di}{dt} = E - v_a \quad (2)$$

$$= E - r_a \cdot i$$

wherein v_a is the instantaneous arc voltage and r_a the instantaneous arc resistance.

Because of the limited insulation level of any electric system, it may be necessary to impose certain limitations as to the instantaneous voltage

$$L \frac{di}{dt}$$

along the inductance. In low voltage systems the permissible inductive voltage may be in the order of several hundred percent of the circuit voltage. It may, however, be assumed that arc resistance r_a be introduced into the circuit at such a rate as to induce exactly the voltage $2E$ in the inductance L . Then

$$L \frac{di}{dt} = E - v_a = -2E \quad (3)$$

10 and

$$v_a = 3E \quad (4)$$

$$i = I - \frac{2E}{L} \cdot t \quad (5)$$

$$r = \frac{3E}{(I - \frac{2E}{L}) \cdot t} \quad (6)$$

$$x = \frac{3E}{r_x (I - \frac{2E}{L}) \cdot t} \quad (7)$$

In the above equations i is the current which flows in the circuit at the time $t=0$ of arc initiation. The value r_x must be determined experimentally. It may be necessary to admit higher induced voltages than $2E$, and the above calculation can be repeated in a similar fashion for any permissible upper limit of the inductive voltage

$$L \frac{di}{dt}$$

A fuse structure of the type shown in Figs. 35 1 and 2 may require special consideration of the problem of limiting the inductive voltage incident upon blowing of the fuse, particularly in case of a fuse used in circuits involving higher circuit voltages than the 600 volt range for which fuses of the present kind are primarily intended. Where a plurality of fuse structures of the present invention are arranged in parallel in a low voltage circuit, the danger of inductive voltage surges is minimized on account of sequential blowing of the fuses and that danger hardly needs any consideration.

The operation of a fuse of the type shown in Figs. 1 and 2 is in substance as follows: On the occurrence of a small but protracted overload say, in the order of 8 to 10 times the rated current of the fuse, a considerable time is required for increasing the temperature of the portions 4a of reduced cross-section to melting temperature. The long time element involved permits a thorough heat exchange between the portions 4a of reduced cross-section and the portions 4b of relatively larger cross-section. Because of that thorough heat exchange, the temperature distribution along the entire length of the fuse link 4 will be relatively even, i. e. the difference between the hottest portions of the link and the coolest portions of the link will be relatively small. In other words, on the occurrence of a relatively small but protracted overload the fuse link 4 will be thoroughly pre-heated along its entire length before melting and arc initiation occurs at the points of reduced cross-section. Because of the preheating of the portions 4b of relatively larger cross-section, a relatively small amount of energy is required after arc initiation at the reduced cross-section portions 4a for converting a certain percentage of the portions 4b into vapor and thus producing the required interrupting gap. The amount of heat stored in the portions 4b prior to arc initiation

greatly reduces the amount of heat that must be generated at the portions 4b after arc initiation to produce the required interrupting gap and hence greatly reduces the arcing time and the arc energy involved in the interruption of over-load currents of relatively small magnitude.

For a better understanding of the operation of fuses according to the present invention reference is made to Fig. 3. Fig. 3 refers to a prior art current-limiting low voltage fuse and shows the voltage gradient at the point of arc initiation plotted against time. The diagram of Fig. 3 was obtained by impulse tests with substantially constant current. The record starts with a voltage gradient of 300 volts per centimeter and drops within 40 milliseconds to less than 15 volts per centimeter. The decrease of the voltage gradient and of the resistance of the arc gap at the point of arc initiation with arcing time is due to progressive heating of the pulverulent arc extinguishing filler at this particular point. Such a decrease of arc resistance at the point of arc initiation must be over-compensated by an increase of the resistance at other points, i. e. by progressive gap elongation resulting from progressive vaporization of the fuse link. That process of gap elongation involves relatively long arcing times and relatively large amounts of arc energy if relatively cold link metal must be vaporized by the heat of the arc. The process of producing a relatively large arc gap involves also the generation of relatively large amounts of metal vapor adverse to arc extinction. Providing a plurality of portions of reduced cross-section along the fuse link and evenly pre-heating of the entire fuse link before the time of arc initiation permits a reduction of both arcing time and arc energy. Reduction of the arcing time, in turn, means that the circuit is interrupted before a serious decay of the voltage gradient at the point of arc initiation has taken place.

The amount of metal which is vaporized in a current-limiting fuse depends, aside from the nature of the pulverulent arc-extinguishing filler, upon the current density in the fuse link. The speed at which the length of the arc gap increases may be expressed by the equation:

$$v = C \cdot \frac{I}{f} \quad (8)$$

wherein v is the speed of growth of the gap length, I the rate of current flow, f the cross-sectional area of the link and C a constant having the dimension cm^3 per amp. The values of the constant C have been determined with various test arrangements and it was found that they varied over a wide range. Large values of C are obtained where the link is pre-heated along its entire length before arc initiation occurs, whereas small values of C are obtained where the portions of the link immediately adjacent the point of arc initiation are relatively cold. This makes it clear why under otherwise similar conditions a link having a plurality of points of reduced cross-section uniformly distributed substantially along the entire length of the link so as to cause an even pre-heating of the entire link in case of relatively small protracted overloads is conducive to a more rapid growth of the total gap length than a link in which relatively cold link metal must be brought up to vaporization temperature to produce the gap length required for final interruption of the circuit. The plurality of portions of reduced cross-section thus have the cumulative effect of limiting the decay of the

voltage gradient at the point of arc initiation and accelerating the speed of gap growth by relatively even pre-heating of substantially the entire length of the link.

The following table indicates the amount of energy in kilowattseconds required for converting one cm^3 of cold silver into silver vapor.

	Kw. seconds
Energy required for raising the temperature from 0 deg. cent. to the fusing point	2.6
Latent heat of melting	1.2
Energy required for raising temperature from fusing point to the boiling point	3.7
Latent heat of vaporization	23.0
Total	30.5

Where small currents are involved, a current-limiting fuse may be expected to work the better, the larger the portion of the total energy required for vaporizing the link is supplied by the circuit prior to arc initiation and the smaller the portion of the total energy required for vaporizing the link is supplied by the circuit in form of arc energy. The geometry of the fuse link shown in Fig. 1 complies evidently well with this requirement.

On the occurrence of a fault current in the nature of a short-circuit current, arc initiation is effected in an extremely short time after inception of the fault. That time is much too short to permit any appreciable pre-heating by heat exchange of portions 4b by heat generated at the portions 4a. Consequently all the energy that is needed for producing the required interrupting gap must be furnished in form of arc energy by the circuit under interruption. The portions 4b serve on the occurrence of fault currents in the nature of short-circuit currents as a means for absorbing large amounts of energy at an extremely rapid rate. They and the filler 6 enable to absorb in much less than half a cycle of the current wave all the magnetic energy inherent in the circuit at the time of arc initiation.

It appears from the foregoing that the relatively large cross-section portions 4b pre-store heat in case of low current circuit interruptions, thus limiting the amount of arc energy that must be furnished by the circuit to effect a complete interruption thereof, while these portions help to absorb the large amounts of energy that are present in the circuit at the time of arc initiation in the case of faults in the nature of short-circuits.

Fig. 4 shows, diagrammatically, the behavior of prior art current-limiting fuses and of current-limiting fuses of the present invention under short-circuit conditions. V represents the generated voltage plotted versus time. The short-circuit is assumed to occur at the time t_1 . The time elapsing between the time of voltage zero t_0 and the time t_1 of fault inception is often expressed in electrical degrees and referred to as fault starting angle θ . The fault starting angle θ has an important effect upon severity of interruption, since it determines the displacement of the short-circuit current. The displacement will be high, i. e. the short-circuit current will be highly asymmetrical, if the fault starting angle θ is close to zero. Fig. 4 refers to a case where the short-circuit tends to be followed by a major current loop indicated by the reference sign I. Where the fault is initiated at the peak of the voltage wave, i. e. where the fault starting angle

θ is 90° , the short-circuit current is fully symmetrical.

When interrupting short-circuit currents maximum severity obtains at such a fault starting angle θ as to cause melting of the fuse link and initiation of arcing shortly prior to, or at the time when the voltage wave V passes through its peak. Maximum severity obtains if arcing is initiated between 70 and 80 degrees on the voltage wave. Fig. 4 clearly refers to two cases where arcing is initiated shortly prior to the time when the voltage wave passes through its peak.

In case of the prior art current-limiting fuse the current rises up to the peak i max. of the let-through current. That peak occurs a few electrical degrees prior to the peak of the voltage wave V . The peak i max. of the let-through current is reached at the time of arc initiation. In the time between arc initiation and the subsequent zero of the voltage wave enough arc resistance is established in the fuse to force the current down to zero. The arc energy released during the time of initiation of the arc and the time of its permanent extinction is an important severity factor. The total arc energy is determined by the equation

$$W = \int_0^T v_a \cdot i_a dt \quad (9)$$

wherein V_a is the arc voltage and i_a the arc current. The total arc energy may be determined from oscillograms by integrating the product of arc voltage V_a and arc current i_a over the entire arcing period.

The peak current at the time of arc initiation is one of the most characteristic data determining the behavior of a current-limiting fuse under short-circuit conditions. The maximum let-through current i' max. of a fuse of the present invention is shown in Fig. 4 to be quite smaller than the maximum let-through current i max. of a prior art current-limiting fuse having the same current and voltage ratings. The arc extinguishing capacity of the arc-extinguishing means, including that of the filler 6 of the fuse of the present invention, are so related to the mass of metal of which the fuse link consists that the arcing time is limited—even under the most onerous short-circuit interrupting conditions to which the fuse may be subjected in the circuit with which it is associated—to the range of 1 to 2 times the time elapsing between initiation of the short-circuit and initiation of arcing. In other words, even if the fault occurs at such a fault starting angle θ as to cause arc initiation close to the peak of the generated voltage, the time required for permanent extinction of the arc will be within the range of 1 to 2 times the time elapsing between initiation of the fault and initiation of arcing.

The drastic reduction of the peak of the let-through current i' max., and the consequent drastic reduction of the arcing time and of the arc energy has been achieved in the fuse of the present invention by drastically reducing the total amount of link metal and particularly the amount of link metal that must be heated up to the time of melting and arc initiation. This drastic reduction in the amount of metal that must be heated to the melting point to initiate arcing is achieved by the provision of the extremely short portions 4a of reduced cross-section of the link 4. These portions do not, in spite of the smallness of their cross-section, result in a relatively low current rating of the fuse

because they are effectively cooled during normal operation of the fuse by the large masses of metal constituted by the immediately adjacent portion 4b of relatively larger cross-section. In other words, the reduced cross-section portions greatly reduce the peak of the let-through current i' max. without affecting the normal current carrying capacity of the fuse. It is possible to minimize the total mass of metal of the link and that present at the reduced cross-section portions 4a to such an extent that the resultant reduction of the peak of the let-through current i' max. causes a limitation of the arcing time to 1 to 1.5 times the time elapsing between initiation of a short-circuit and initiation of arcing. By sufficiently reducing the total mass of link metal and particularly the mass of metal at the points 4a such a limitation may be caused even where the short-circuit is initiated at such a lead angle that initiation of arcing occurs substantially at, or just before, the peak of the voltage wave V .

When reviewing random oscillograms showing the operation of prior art current-limiting fuses having conventional fuse links it is possible to discover some interruptions wherein the arc lasts not longer than 1 to 1.5 times the time elapsing between fault initiation and arc initiation. In the prior art current-limiting fuses such short arcing times can only be observed where the interrupting conditions are not severe, i. e. when arc initiation occurs relatively close to the zero of the voltage wave V . In fuses of the present invention the arcing time is as short under the most onerous or severe interrupting conditions as with prior art current-limiting fuses under most favorable or relatively favorable interrupting conditions. This is due, as previously mentioned, to a proper balance between the arc extinguishing capacity of the arc extinguishing means, particularly the pulverulent filler within the fuse casing, and the peak of the let-through current. Since the arc extinguishing capacity of the arc extinguishing means cannot be greatly changed—it is mainly determined by the thermal characteristics of the best grade of quartz sand used as a fuse filler—the peak of the let-through current had to be brought down by appropriate reduction of the mass of metal melted prior to initiation of arcing under short-circuit conditions to enable shortening of the arcing time and reduction of the arc energy beyond the limits attained in prior art fuses. By properly designing the restricted cross-section portions 4a of the link 4 the arcing time may consistently be limited to 1 to 1.5 times the time elapsing between fault initiation and arc initiation even where the fault is initiated at such a lead angle that initiation of arcing occurs within the range of 20 degrees prior and 10 degrees after the peak of the voltage wave V .

In order to control the let-through current to an extent which will effect a consistent reduction of the arcing time of a high current carrying capacity current-limiting low voltage fuse, the amount of metal in the fuse link must be reduced to a minimum by reducing the length of the fuse link as much as possible. There is a maximum critical link length for fuses having a voltage rating within the limits of 600 and 1000 volts. That maximum critical link length is about 2 inches.

In the modification of the structure of Figs. 1 and 2 which is shown in Fig. 5, each of the reduced cross-section portions is constituted by a pair of parallel current paths 4a' and 4a''. Be-

cause of the subdivision of the portions of reduced cross-section into two parallel current paths $4a'$ and $4a''$, upon melting of the current paths $4a'$ and $4a''$ two parallel arclets will be initiated. It is well known that arcs in parallel are unstable and this tends to facilitate arc extinction. Because of small differences due to manufacturing tolerances between the current paths $4a'$ and $4a''$, there tends to be a slight difference between the time when arclets are initiated at these two points. Similarly, extinction of the arclets formed at these two points occurs sequentially rather than simultaneously. Sequential initiation and sequential extinction of the pair of arclets formed at each point of restricted cross-section of the fuse link tends to limit the rate of change of current

$$\frac{di}{dt}$$

and therefore to limit inductive voltage surges incident upon interruption of relatively highly inductive circuits.

As shown in Fig. 5, the fuse link 4 has a plurality of rectangular perforations 8 arranged along the center line thereof. These perforations are spaced substantially equidistantly and extend substantially along the entire length of the link. Each perforation 8 is laterally bounded by a pair of conductive elements forming two separate parallel current paths $4a'$, $4a''$. The cross-section of these parallel current paths $4a'$ and $4a''$ is much less than the cross-section of the portions $4b$ of the link arranged intermediate the perforated portions thereof. The length of each intermediate portion $4b$ is a multiple of the length of each perforated portion. The total length of the perforated portions and of the intermediate non-perforated portions exceeds the length of the link which is vaporized under the most onerous circuit interrupting conditions to which the fuse may be subjected in the circuit with which it is associated. The portions of the link 4 which remain substantially intact, i. e. which are not vaporized even if the fuse is subjected to the most onerous interrupting conditions which the circuit can produce which the fuse is called to protect are indicated by cross-hatching in Fig. 5. The above may also be expressed by saying that the serially related arclets which form at the reduced cross-section or reduced width portions of the ribbon-type fuse link never merge into one single long arc, this being due to the relative length of the larger cross-section or larger width portions of the link.

As previously mentioned, upon blowing of the fuse under short-circuit conditions, the pulverulent arc extinguishing filler 6 forms a fulgurite, or rather a plurality of aligned fulgurites. In order to obtain a fuse structure which is as compact as possible, the diameter of the casing 3 should be substantially equal to the diameter of the fulgurite or fulgurites formed by the filler 6 upon vaporization of the link under the action of a current of short-circuit current proportions. In prior art current-limiting fuses the diameter of the casing is generally much larger than the diameter of the fulgurite or fulgurites formed within the casing, since it was thought, heretofore, that it is necessary to provide a large excess of filler, for cooling sufficiently the gaseous products of arcing, i. e. a large amount of filler not melted under short-circuit conditions and not converted into a fulgurite. It has not only been

found that this is not correct, but that it is desirable, for reasons other than that of compactness of design, to limit the diameter of the casing substantially to that of the fulgurite or fulgurites formed upon vaporization of the fuse link under short-circuit conditions. The larger the diameter of the casing in excess of the diameter of the fulgurite, the larger the heat dissipating ability of the fuse structure, the larger the amount of heat which must be generated by I^2r losses within the fuse to obtain the desired current-time characteristic. Therefore, in order to minimize I^2r losses, the diameter of the casing 3 should only slightly exceed the diameter of the fulgurite or fulgurites which form when a current-limiting fuse is subjected to a short-circuit current.

The casing 3 is preferably made of an organic combustible material, such as hard fiber. The diameter of the casing 3 should slightly exceed the diameter of the fulgurite or fulgurites formed upon blowing of the fuse, not more than necessary to preclude substantial scorching of the material of which the casing 3 is made by the fulgurite or fulgurites which form when the fuse blows. Hard fibre and other organic materials evolve gases under the action of heat and gases which may evolve from casing 3 tend to provide a protective layer between the casing and the fulgurite formed therein, reducing the tendency of the former to be destroyed by the heat of the latter.

In a fuse of the type shown in Figs. 1, 2 and 5, where the fuse link 4 is provided with a plurality of reduced cross-section portions, the diameter of the fulgurite or fulgurites is in the order of the distance between the reduced cross-section portions of the link. Hence the diameter of casing 3 should be in the order of the distance between the reduced cross-section portions.

Fig. 6 illustrates the features of the invention embodied in a current-limiting fuse having a relatively small current rating. The fusible element has but three portions $4a$ of restricted cross-section. These portions are formed by circular perforations rather than by rectangular perforations, as shown in Fig. 5.

The fuse illustrated in Figs. 7 and 8 comprises a link 4 having five portions $4a'$, $4a''$ of restricted cross-section formed by provision of five circular perforations in the fuse link. The perforation situated in the center of the link 4 is provided with a rivet-like insert 10 as can best be seen in Fig. 8. Insert 10 consists of a metal having a lower fusing point than the metal of which the fuse link 4 is made and adapted to form an alloy with the metal of which the fuse link 4 is made having a lower fusing point than the metal of which the fuse link 4 is made.

In a fuse as shown in Figs. 1, 2, 5 and 6 the point having the highest temperature is the zone of restricted cross-section situated midway between the ends of the fuse link 4 . It is at this point that arcing is initiated at the occurrence of very small overloads of inadmissible duration. Insert 10 , owing to its heat absorbing capacity, delays the rate of increase in temperature of the middle portion of the fuse link. When insert 10 melts at a given temperature, its melting results in the formation with metal of which link 4 is made of an alloy having a relatively low melting temperature. This is conducive to rapid fusion of the middle portion of the link 4 , once insert 10 has reached its melting point.

The insert 10 may consist of a suitable eutectic

alloy to achieve interruption of the circuit at a temperature which can be predetermined with a high degree of accuracy. However, satisfactory results may also be obtained with a tin insert in a link of silver.

In prior art fuses comprising a metal having a relatively low fusing point intended to form upon fusion thereof with a high fusing point metal a low fusing point alloy, formation of the alloy took generally place during normal operation of the fuse rather than at the time when the fusing temperature of the low fusing point metal was reached. Such a gradual conversion of two metals having different fusing points into an alloy having a relatively low fusing point is highly objectionable since it results in a gradual change of the current-time characteristic of the fuse. An objectionable change of that kind of the current-time characteristic of a fuse is often referred-to as "aging." The structure of Figs. 7 and 8 is characterized in that it minimizes, or completely avoids, "aging" of the fuse. This is probably due to the fact that the surface along which there is immediate contact between the two metals is minimized as long as the rivet-like insert 10 is unfused. The shank 10a of rivet-like insert 10 is probably covered with an oxide film tending to preclude the insert from reacting with the surrounding metal of which the fuse link 4 is made. This tendency is increased by the formation of a small gap between the shank 10a of the rivet-like insert 10 and the surrounding fuse metal. The upset head 10b of rivet-like insert 10 can effectively be separated and isolated from the adjacent metal of which the fuse link 4 is made by means of a layer 11 of a suitable fluxing agent, such as rosin. That layer 11 prevents interaction of the two metals and formation of an alloy only as long as fusion of insert 10 has not taken place, but is conducive to extremely rapid formation of an alloy when insert 10 ultimately melts during a period of a small but protracted overload.

Sound design of a fuse requires that the amount of heat generated therein while it is carrying current of permissible magnitude be minimized, and that whatever heat is generated therein be dissipated in such a way as to keep the fuse reasonably cool while it is carrying current. In high capacity and particularly current-limiting fuses an additional problem of a thermal nature arises. When such a fuse is caused to blow by a fault current of short-circuit current proportions, a relatively large amount of heat is generated within the fuse at an almost explosive rate, and therefore the temperature prevailing within the fuse tends to be high. If blowing of a fuse by a fault current of short-circuit current proportions is preceded by a small protracted overload, the temperature of the portion of the fuse tube or casing midway between its ends tends to be already relatively high before an additional large amount of heat is released in explosion-like fashion. There is a general tendency, particularly under the above described conditions, that fuse tubes or casings of current-limiting fuses become damaged, i. e. charred, shortly after successful circuit interruption has occurred, when the heat generated during the interrupting process at the arcing zone is transferred to the axially inner portion of the fuse tube or casing, where the temperature always tends to be highest. Such damage can be prevented by providing a good thermal insulation between the axially inner portion of the link and the fuse tube or casing, thus divert-

ing the destructive radial heat flow that tends to occur after blowing of a fuse in a direction longitudinally of the link and precluding overheating of the center portion of the fuse tube or casing. This is achieved in the embodiment of the present invention shown in Fig. 9 by providing different arc-extinguishing pulverulent fillers 12 and 6 within the fuse or casing 3, i. e. gypsum at the axially inner portion and quartz sand at the axially outer portion. Gypsum has a much smaller thermal conductivity than quartz sand and thus protects effectively the most endangered portion of the fuse tube or casing 3 against excessive heating. Quartz sand is a far more effective cooling and deionizing medium than gypsum and ensures the current-limiting action of the fuse. Quartz sand is a fulgurite-forming substance which evolves virtually no gas under the heat of the arc, while gypsum is not fulgurite-forming and evolves relatively large amounts of gas under the heat of the arc. The combination of quartz sand and gypsum or similar gas evolving substances evolving relatively large amounts of gas under the heat of the arc renders it possible to control with great accuracy the amount of gas generated as well as the amount of gas pressure within the casing.

It was believed, heretofore, that current-limiting fuses should preferably not be provided with gas evolving fillers, i. e. fillers which evolve appreciable amounts of gas under the heat of the arc, because of the difficulties involved in limiting the pressure within the casing below dangerous pressure levels, i. e. pressures which involve the danger of bursting of the casing or fuse tube. To provide current-limiting fuses only with quartz sand or similar non-gas-evolving fillers means to forego the advantages resulting from the increased dielectric strength of gases under pressure. The structure of Fig. 9 permits to combine effective current-limiting action with controlled generation of gas within the casing or fuse tube 3. The pulverulent fulgurite-forming arc-extinguishing filler 6 surrounds all the reduced cross-section portions 4a of the link but one. The pulverulent gas evolving non-fulgurite forming filler 12 surrounds but one reduced cross-section portion of the link. Preferably fillers 6 and 12 are separated by a pair of insulating barriers 12a.

In addition to precluding charring of the center portion of the fuse tube or casing 3 and of causing a limited rise of pressure therein, the arrangement shown in Fig. 9 comprising arc-extinguishing fillers 6, 12 having different properties, at different points of the fuse tube or casing 3, has a further important advantage. The fulgurite or fulgurites formed in current-limiting fuses are relatively good conductors of electricity. They lose their conductivity relatively rapidly with decreasing temperature. If the rate of decrease of temperature of a fulgurite is not sufficiently rapid, a small current will continue to flow through the fulgurite for a short time after extinction of the arc and interruption of the circuit have been achieved. That small, undesirable current is often referred to as the "follow current." The gypsum filler 12 in the structure of Fig. 9 has a relatively small energy absorbing capacity, but it provides an effective insulating barrier between the fulgurites formed on both sides thereof and thus precludes the flow of a "follow current" while the fulgurites are still relatively hot and semi-conductive.

It is well known in the art of current-limiting fuses to surround the middle or center portion of the fuse link with a thermal insulator, e. g. glass beads. This is, however, done for controlling the fusing characteristics of the link rather than for any of the aforementioned purposes.

The fuse units shown in Figs. 1, 2, 5 and 6 to 9 have a relatively small current carrying capacity. These fuse units are intended to be combined into a composite current-limiting fuse where a relatively high current-carrying capacity is required. Such a composite high current-carrying capacity current-limiting fuse is formed by an assembly of a plurality of identical separate fuse units adapted to be arranged in parallel in an electric circuit. An embodiment of such an assembly or composite fuse is shown in Figs. 10 and 11. A structure of the kind shown in these figures is capable of carrying continuously 4,000 R. M. S. amps., and if desired even much higher currents.

Referring now to Figs. 10 and 11, the composite fuse comprises two terminal elements 15 arranged on opposite ends of an outer shell or housing 16. The terminal elements 15 are in the form of cylindrical caps integral with knife blade contacts 15a adapted to be inserted in a suitable fuse holder (not shown). Shell 15 is secured to terminal elements 15 by screws 18 or the like. A plurality of fuse units 20 of the type shown in Figs. 1, 2, 5 and 6 to 9 is arranged within the shell or housing 16. These units are adapted to bridge or inter-connect terminal elements 15, thus being arranged in parallel in the electric circuit to be protected. Each said units 20 comprises a casing member 3, terminals caps 1, 2 on opposite ends thereof, a fuse link 4 having a plurality of portions 4a of restricted cross-sectional area arranged within said casing member 3 and a pulverulent arc-extinguishing filler 6 likewise arranged within casing member 3 and surrounding link 4. The upper terminal caps 2 of the fuse units 20 are in contact with the upper, and the lower terminal caps 1 of the fuse units 20 are in contact with the lower, terminal element 15. These fuse units 20 are grouped in spaced relation to form a pattern of concentric shells, 17, 17a, 17b, etc., to cause the total current flowing through said fuse units 20 to be unequally distributed among fuse units 20 pertaining to different shells 17, 17a, 17b, etc. This, in turn, causes fusion of the portions 4a of restricted cross-sectional area of links 4 of fuses 20 pertaining to different shells 17, 17a, 17b, etc. to occur at slightly different points of time. These time differentials are helpful in limiting the rate of change

$$\frac{di}{dt}$$

of the total current at the time the peak of the let-through current is reached, thus limiting the magnitude of possible inductive voltage surges. The arrangement of individual fuse units 20 in a pattern of concentric shells tends also to establish a magnetic blowout effect by which the arc stream formed in each individual fuse unit 20 is impelled in a lateral direction and its rate of deionization is increased. This magnetic blow-out effect and the unequal distribution of the total current among the individual fuse units 20 by which the composite assembly is constituted may be further increased if the current path through the holder for the fuse and

the fuse is substantially U-shaped, resulting in a magnetic loop action upon the arc current in each individual fuse unit 20. The spaces between the casings 3 of the individual fuse units 20 are filled with a granular inorganic cooling substance 19, such as quartz sand, tending to maintain the fuses in their shell pattern and providing a safety feature in case that the casing 3 of any of the individual fuse units 20 should accidentally burst on account of an excess of pressure generated therein.

As previously mentioned, current-limiting fuses are generally filled with quartz sand to the exclusion of any arc-extinguishing substance which evolves substantial amounts of gas under the heat of the arc as, for instance, gypsum or marble powder. The arrangement shown in Fig. 9 of a quartz filler at the axially outer ends of the casing and of a gas-evolving filler midway between the ends thereof is a first step toward an accurately pressure-controlled current-limiting fuse. The second step consists in providing venting means in the nature of a safety valve of utmost simplicity and reliability in combination with means for precluding any damage, such as occurrence of an electric breakdown, resulting from the egress of extremely hot arc products from the casing of the individual fuse units 20. In the structure of Figs. 10 and 11 the terminal caps 1 and 2 of the individual fuse units 20 are but relatively loosely secured to the casings 3 of the individual fuse units. The casing 3 and either one, but preferably both, terminal caps 1 and 2 of each fuse unit 20 define a small leakage gap therebetween. This leakage path permits a restricted escape of hot gases evolved within any casing 3 to the body of sand 19 by which the individual fuse units are surrounded. Such a venting arrangement is obviously much less expensive to provide than the conventional prior art venting arrangements in non current-limiting fuses which comprise small venting holes in their terminal caps. The labyrinth leakage path resulting from relatively loosely mounting the terminal caps 1 and 2 on the casings 3 is much more effective in cooling of hot gases and in preventing loss of pulverulent arc-extinguishing filler than any prior art venting means has been. The provision of the body of sand 19 immediately adjacent the circular outlet of the safety leakage gap formed between the caps 1 and 2 and the casings 3 is of vital importance as evidenced by the occasional formation of a ring of melted or chemically affected sand immediately adjacent the circular outlet of the safety leakage gap.

Reference is made to copending application Serial No. 60,328, filed November 16, 1948, for a more detailed disclosure of the composite structure of Figs. 10 and 11.

It will be understood that, although but a few embodiments of this invention have been shown and described in detail, the invention is not limited thereto and that the illustrated embodiments may be modified or other embodiments made without departing from the spirit and scope of the invention as set forth in the accompanying claims.

It is claimed:

1. In combination an electric circuit having a circuit voltage not exceeding the 600 volt range, a current-limiting fuse arranged in said circuit, said fuse comprising a casing, terminal elements on opposite ends of said casing, a fuse link interconnecting said terminal elements and having a plurality of portions of reduced cross-section

spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuiting current of said circuit, each said relatively larger cross-section portion having a length being a multiple of the length of said reduced cross-section portions, a pulverulent arc-extinguishing filler within said casing surrounding said links, said filler having a sufficiently high arc-extinguishing capacity in relation to the number of points of arc initiation to effect extinction of any short-circuit arc that said circuit is capable of producing in less than $\frac{1}{120}$ of a second after the time of fault inception, the total length of said reduced cross-section portions and said relatively larger cross-section portions exceeding the length of said link vaporized under the most onerous circuit interrupting conditions to which said fuse may be subjected in said circuit.

2. In combination an electric A.-C. circuit having a circuit voltage not exceeding the 600 volt range, a current-limiting fuse arranged in said circuit, said fuse comprising a casing, terminal elements on opposite ends of said casing, a fuse link interconnecting said terminal elements and having a plurality of portions of reduced cross-section spaced substantially equidistantly along substantially the entire length of said link and a plurality of portions of relatively larger cross-section intermediate said reduced cross-section portions, each said reduced cross-section portion having a sufficiently small cross-sectional area to initiate arcing at instantaneous currents far below the available short-circuit current of said circuit, each said relatively larger cross-section portion having a length being a multiple of the length of said reduced cross-section portions, a pulverulent arc-extinguishing filler within said casing surrounding said link, said filler having a sufficiently high arc-extinguishing capacity in relation to the arcs initiated at said portions of reduced cross-section to effect complete interruption of any short-circuit current that said circuit is capable of producing in less than one half cycle of the current wave after the time of fault inception, the total length of said reduced cross-section portions and of said relatively larger cross-section portions exceeding the length of said link vaporized under the most onerous circuit interrupting conditions to which said fuse may be subjected in said circuit.

3. In combination an electric circuit, a current-limiting fuse arranged in said circuit, said fuse comprising a casing, terminal elements on opposite ends of said casing, a fuse link interconnecting said terminal elements and having a plurality of portions of reduced cross-section and a plurality of portions of relatively larger cross-section intermediate said reduced cross-section portions, each said reduced cross-section portions having a sufficiently small cross-sectional area to initiate arcing at instantaneous currents far below the available short-circuit current of said circuit and each said reduced cross-section portions being constituted by a pair of conductive elements forming separate parallel current paths, each said relatively larger cross-section portions having a length being a multiple of the length of said reduced cross-section portions, a pulverulent arc-extinguishing filler within said casing sur-

rounding said link, said filler having a sufficiently high arc-extinguishing capacity in relation to the arcs initiated at said portions of reduced cross-section to effect permanent interruption of any short-circuit current that said circuit is capable of producing in less than $\frac{1}{120}$ of a second after the time of fault inception, the total length of said reduced cross-section portions and of said relatively larger cross-section portions exceeding the length of said link vaporized under the most onerous circuit interrupting conditions to which said fuse may be subjected in said circuit.

4. In combination an electric circuit, a current-limiting fuse arranged in said circuit, said fuse comprising a casing, terminal elements on opposite ends of said casing, a fuse link interconnecting said terminal elements, said link having along the center line thereof a plurality of rectangular perforations spaced substantially equidistantly and extending substantially along the entire length of the link, each said perforations being laterally bounded by a pair of conductive elements forming separate parallel current paths, said elements having a sufficiently small cross-sectional area to initiate arcing before a short-circuit current reaches the available short-circuit current of said circuit, the portions of said link situated intermediate said perforated portions thereof having a length being a multiple of the length of said perforated link portions, a pulverulent arc-extinguishing filler within said casing surrounding said link, said filler having a sufficiently high arc-extinguishing capacity in relation to the arcs initiated at said portions of reduced cross-section to effect permanent interruption of any short-circuit current that said circuit is capable of producing in less than $\frac{1}{120}$ of a second after the time of fault inception, the total length of said perforated portions and of said intermediate portions exceeding the length of said link vaporized under the most onerous circuit interrupting conditions to which said fuse may be subjected in said circuit.

5. A current-limiting fuse comprising a casing, terminal elements on opposite ends of said casing, a pulverulent arc-extinguishing filler within said casing, a fuse link within said casing interconnecting said terminal elements and being surrounded by said filler, said fuse link having a plurality of portions of reduced cross-section and a plurality of portions of relatively large cross-section intermediate said reduced cross-section portions, each said relatively larger cross-section portions having a length being a multiple of the length of said reduced cross-section portions, and each said reduced cross-section portions being constituted by a pair of conductive elements forming separate parallel current paths.

6. A high current carrying capacity current-limiting fuse having a voltage rating of 600 to 1000 volts comprising a casing, terminal elements on opposite ends of said casing, a pulverulent arc-extinguishing filler within said casing, a fuse link within said casing interconnecting said terminal elements and being surrounded by said filler, said fuse link comprising a plurality of portions of reduced cross-section each being constituted by a pair of conductive elements forming separate parallel current paths, said link comprising at least one portion of relatively larger cross-section intermediate said reduced cross-section portions, said relatively larger cross-section portion having a length being a multiple of the length of said reduced cross-section portions,

the total length of said link being approximately two inches.

7. A high current carrying capacity current-limiting fuse having a voltage rating of 600 to 1000 volts comprising a casing, terminal elements on opposite ends of said casing, a pulverulent arc-extinguishing filler within said casing, a fuse link within said casing interconnecting said terminal elements and being surrounded by said filler, said link comprising at least two portions having rectangular perforations and at least one portion of relatively larger cross-section between said perforated portions, the length of said relatively larger cross-section portion being a multiple of the length of each said perforated portions and the total length of said link being no greater than two inches.

8. A high current carrying capacity current-limiting fuse having a voltage rating between 600 and 1000 volts comprising a casing, terminal elements on opposite ends of said casing, a pulverulent arc-extinguishing filler within said casing, a fuse link within said casing interconnecting said terminal elements and being surrounded by said filler, said link having along the center line thereof a plurality of perforations, each said perforation being laterally bounded by a pair of conductive elements forming separate parallel current paths, said link further comprising a portion of relatively larger cross-section between each pair of said perforations, the length of said relatively larger cross-section portion being a multiple of the length of each said perforation and the total length of said link being no greater than two inches, and the mass of said link being sufficiently small and the arc-extinguishing capacity of said filler being sufficiently large to limit the arcing time to 1 to 2 times the time elapsing between fault inception and arc initiation when said fuse is subjected to the most severe interrupting conditions of the circuit for which said fuse is intended.

9. A high current carrying capacity current-limiting fuse having a voltage rating between 600 and 1000 volts comprising a casing, terminal elements on opposite ends of said casing, a pulverulent arc-extinguishing filler within said casing, a fuse link within said casing interconnecting said terminal elements and being surrounded by said filler, said link having a plurality of portions of uniformly reduced cross-section and at least one intermediate portion of relatively larger cross-section, said reduced cross-section portions having a length being a fraction of the length of said relatively larger cross-section portion, the total length of said link being no greater than two inches, and the mass of said link being sufficiently small and the arc-extinguishing capacity of said filler being sufficiently large to limit the arcing time to 1 to 2 times the time elapsing between fault inception and arc initiation when said fuse is subjected to the most severe interrupting conditions that the circuit for which said fuse is intended is capable of producing.

10. In combination an electric circuit, a current-limiting fuse arranged in said circuit, said fuse comprising a casing, terminal elements on opposite ends of said casing, a fuse link interconnecting said terminal elements and having a plurality of portions of reduced cross-section, arc-extinguishing means of predetermined arc-extinguishing capacity including a pulverulent filler within said casing surrounding said link, the mass of metal of said link being sufficiently small and the arc-extinguishing capacity of said

arc-extinguishing means being sufficiently large to limit the arcing time to 1 to 2 times the time elapsing between fault inception and arc initiation when said fuse is subjected to the most severe interrupting conditions which can be produced by said circuit.

11. A current-limiting fuse comprising a casing, terminal elements on opposite ends of said casing, a fuse link within said casing interconnecting said terminal elements, said fuse link having a plurality of portions of reduced cross-section and a plurality of portions of relatively large cross-section intermediate said reduced cross-section portions, arc-extinguishing means of predetermined arc-extinguishing capacity including a pulverulent filler within said casing surrounding said link, the mass of metal of said link being sufficiently small to limit the peak of the let-through current to sufficiently low values to enable said arc-extinguishing means to effect complete arc extinction in 1 to 1.5 times the time elapsing between initiation of a short-circuit and initiation of arcing when the short-circuit is initiated at such a lead angle that initiation of arcing occurs substantially at or just before the peak of the voltage wave.

12. A current-limiting fuse comprising a casing, terminal elements on opposite ends of said casing, a fuse link within said casing interconnecting said terminal elements, said fuse link having a plurality of portions of reduced cross-section spaced substantially equidistantly along substantially the entire length of said link and a plurality of portions of relatively larger cross-section intermediate said reduced cross-section portions, the length of each said reduced cross-section portion being a small fraction of the length of said relatively larger cross-section portions, arc-extinguishing means of predetermined arc-extinguishing capacity including a pulverulent filler within said casing surrounding said link, the mass of said link being sufficiently small to limit the peak of the let-through current to sufficiently low values to enable said arc-extinguishing means to effect complete arc extinction in 1 to 1.5 times the time elapsing between initiation of a short-circuit and initiation of arcing, the short-circuit being initiated at such a lead angle that initiation of arcing occurs within the range of 20 degrees prior to and 10 degrees after the peak of the generated voltage.

13. A current-limiting fuse comprising a tubular casing, terminal elements on opposite ends of said casing, a fuse link within said casing interconnecting said terminal elements, a pulverulent arc-extinguishing fulgurite-forming filler surrounding said link, the diameter of said casing being substantially equal to the diameter of the fulgurite formed by said filler upon vaporization of said link under the action of a current of short-circuit current proportions.

14. A current-limiting fuse comprising a tubular casing of an organic combustible material, terminal elements on opposite ends of said casing, a fuse link within said casing interconnecting said terminal elements, said link having a plurality of portions of reduced cross-section, a pulverulent arc-extinguishing fulgurite-forming filler surrounding said link, the diameter of said casing being substantially equal to the diameter of the fulgurite formed upon interruption of a short-circuit current and just sufficiently large to preclude substantial scorching by said fulgurite of the material of which said casing is made.

15. A current-limiting fuse comprising a tubular casing, terminal elements on opposite ends of said casing, a fuse link within said casing interconnecting said terminal elements, said link having a plurality of portions of reduced cross-section and a plurality of portions of relatively larger cross-section intermediate said reduced cross-section portions, a pulverulent arc-extinguishing fulgurite-forming filler surrounding said link, the diameter of said casing being in the order of the distance between said reduced cross-section portions of said link to limit the size of said casing to the size required by the formation of a fulgurite upon vaporization of said link under the action of a current of short-circuit current proportions.

16. A current-limiting fuse comprising a tubular casing of an organic combustible material, terminal elements on opposite ends of said casing, a fuse link interconnecting said terminal elements and having a plurality of portions of reduced cross-section and a plurality of portions of relatively larger cross-section intermediate said reduced cross-section portions, a pulverulent arc-extinguishing fulgurite-forming filler surrounding said link, the diameter of said casing exceeding the diameter of the fulgurite formed by said filler upon vaporization of said link under the action of a short-circuit current only to the extent required for precluding scorching of said casing by said fulgurite.

17. A current-limiting fuse comprising a casing, terminal elements on opposite ends of said casing, a metallic fuse link interconnecting said terminal elements and having a plurality of portions of reduced cross-section and a plurality of portions of relatively larger cross-section intermediate said reduced cross-section portions, each said reduced cross-section portions having a hole laterally bounded by a pair of current paths in parallel, the length of each said relatively larger cross-section portions being a multiple of the length of said reduced cross-section portions, a pulverulent arc-extinguishing filler within said casing surrounding said link, and an insert arranged in said hole of at least one of said reduced cross-section portions, said insert consisting of a metal having a lower fusing point than the metal of which said fuse link is made and being adapted to form an alloy with the metal of which said fuse link is made having a lower fusing point than the metal of which said fuse link is made.

18. A current-limiting fuse comprising a casing, terminal elements on opposite ends of said casing, a pulverulent arc-extinguishing filler within said casing, a metallic fuse link within said casing interconnecting said terminal elements and being surrounded by said filler, said link having along the center line thereof a plurality of perforations spaced substantially equidistantly and extending substantially along the entire length of said link, and a rivet-like insert arranged in one of said perforations, said insert consisting of a metal having a lower fusing point than the metal of which said fuse link is made and being adapted to form an alloy with the metal of which said fuse link is made having a lower fusing point than the metal of which said fuse link is made.

19. In a current-limiting fuse the combination of a casing, a pair of terminal elements arranged on opposite ends of said casing, a fuse link within said casing interconnecting said terminal elements, and an arc-extinguishing filler

within said casing and surrounding said link, said filler comprising a pulverulent substance having relatively small heat conductivity arranged in one portion of said casing between said casing and a portion of said link and an inert pulverulent substance having a relatively large heat conductivity arranged in said casing between said casing and the remainder of said link.

20. In a current-limiting fuse the combination of a casing, a pair of terminal elements arranged on opposite ends of said casing, a ribbon-type multiperforated fuse link within said casing interconnecting said terminal elements, and an arc-extinguishing filler within said casing, said filler consisting of quartz sand at the axially outer ends of said link in immediate contact therewith and of a pulverulent substance having a smaller heat conductivity than said sand at the axially inner portion of said link.

21. In a current-limiting fuse the combination of a casing, a pair of terminal elements arranged on opposite ends of said casing, a ribbon-type multiperforated fuse link within said casing interconnecting said terminal elements, and an arc-extinguishing filler within said casing, said filler consisting of a pulverulent fulgurite-forming substance associated with the axially outer portions of said link and in immediate contact therewith and of a pulverulent substance of smaller heat conductivity but larger gas evolving capacity than said fulgurite-forming substance associated with the axially inner portion of said link.

22. In a current-limiting fuse the combination of a casing, a pair of terminal elements arranged on opposite ends of said casing, a ribbon-type fuse link within said casing interconnecting said terminal elements, and an arc-extinguishing filler within said casing, said filler consisting of quartz sand at the axially outer portions of said link and of gypsum powder at the axially inner portions thereof.

23. In a current-limiting fuse the combination of a casing, a pair of terminal elements arranged on opposite ends of said casing, a fuse link within said casing interconnecting said terminal elements, said link having a plurality of relatively short reduced cross-section portions and a plurality of relatively long large cross-section portions alternating with said reduced cross-section portions, and an arc-extinguishing filler within said casing, said filler consisting of a pulverulent fulgurite-forming substance at the axially outer ends of said link and of a pulverulent substance of smaller heat conductivity but larger gas evolving capacity than said fulgurite forming substance midway between the axially outer ends of said link.

24. In a current-limiting fuse the combination of a casing, a pair of terminal elements arranged on opposite ends of said casing, a fuse link within said casing interconnecting said terminal elements, said link having a plurality of relatively short reduced cross-section portions and a plurality of relatively long large cross-section portions alternating with said reduced cross-section portions, a pulverulent fulgurite-forming arc-extinguishing filler within said casing surrounding all said reduced cross-section portions of said link but one, and a pulverulent gas-evolving non fulgurite-forming arc-extinguishing filler within said casing surrounding but one of said reduced cross-section portions.

25. In a current-limiting fuse the combina-

tion of a casing, a pair of terminal caps arranged on opposite ends of said casing, a fuse link within said casing interconnecting said terminal caps, a pulverulent fulgurite-forming non gas evolving filler within said casing surrounding one portion of the length of said link, a pulverulent non fulgurite-forming gas evolving filler within said casing surrounding another portion of the length of said link, a substantially pulverulent cooling substance outside of and surrounding said casing, and means providing from the inside of said casing a restricted leakage path between said casing and at least one of said terminal caps to said cooling substance outside of said casing.

26. In a current-limiting fuse the combination of a casing, a pair of terminal caps arranged on opposite ends of said casing, a fuse link within said casing interconnecting said terminal caps, said link having a plurality of relatively short reduced cross-section portions and a plurality of relatively long large cross-section portions alternating with said reduced cross-section portions, a pulverulent fulgurite-forming arc-extinguishing filler within said casing surrounding all said reduced cross-section portions of said link but one, a pulverulent gas-evolving non fulgurite-forming arc-extinguishing filler within said casing surrounding but one of said reduced cross-section portions, a substantially pulverulent inorganic cooling substance outside of and surrounding said casing, said casing and at least one of said terminal caps defining a small leakage gap therebetween permitting restricted escape of gases evolved from said gas evolving filler to said cooling substance.

27. A current-limiting fuse comprising a casing, terminal elements on opposite ends of said casing, a ribbon-type metallic fuse link interconnecting said terminal elements and surrounded by a pulverulent arc-quenching filler of high cooling capacity, said link having a plurality of substantially equidistant perforations arranged along the center line thereof extending along a predominant portion of the length of said link and defining a plurality of serially related pairs of parallel current paths bounded at each side thereof by one of the lateral edges of said link, and a metal means arranged in contact with said link at the area of one of said plurality of pairs of parallel current paths, said means being of a metal having a lower fusing point than the metal of which said link is made and adapted to form an alloy with the metal of which said link is made having a lower fusing point than the metal of which said link is made, whereby fusing is initiated on relatively small protracted overloads at a point of said link where one of said pairs of parallel current paths is located.

28. A current-limiting fuse comprising a casing, terminal elements on opposite ends of said casing, a ribbon-type fuse link of silver interconnecting said terminal elements and surrounded by a pulverulent quartz filler along a predominant portion of the length thereof, said link having a plurality of substantially equidistant perforations extending along substantially the entire length of said link and defining a plurality of serially related pairs of parallel current paths bounded at each side thereof by one of the lateral edges of said link, and metal means in contact with said link adapted to form an alloy with silver having a lower fusing point than silver, said metal means being arranged at the area of one of said pairs of parallel current paths to cause initial fusion of said link at the occurrence of relatively

small protracted overloads at said one of said pairs of parallel current paths.

29. A current-limiting fuse comprising a casing, terminal elements on opposite ends of said casing, a ribbon-type fuse link of silver interconnecting said terminal elements and surrounded at least in part by a pulverulent quartz filler, said link having a plurality of substantially equidistant perforations extending along a predominant portion of the length of said link and defining a plurality of serially related pairs of parallel current paths bounded at each side thereof by one of the lateral edges of said link, and metal means in contact with said link adapted to form a silver-tin alloy with the silver of which said link is made, said metal means being arranged at the area of one of said pairs of parallel current paths to cause initial fusion of said link at relatively small protracted overloads at the point thereof where said one of said pairs of parallel current paths is located.

30. A current-limiting fuse comprising a casing, terminal elements on opposite ends of said casing, a pulverulent arc-quenching filled within said casing, a fuse link within said casing interconnecting said terminal elements and being surrounded by said filler, said link having a plurality of portions of minimum cross-section spaced substantially along the entire length of said link, a plurality of portions of maximum cross-section each alternating with one of said plurality of minimum cross-section portions, and a plurality of portions of progressively varying cross-section arranged between said minimum cross-section portions and said maximum cross-section portions, said plurality of minimum cross-section portions and said plurality of progressively varying cross-section portions defining a plurality of serially related pairs of parallel current paths, one of said plurality of pairs of parallel current paths being associated with fusing point affecting metal means for causing initial fusion of said link at the occurrence of small protracted overloads only at the point of said link where said one of said plurality of pairs of parallel current paths is located.

31. A high current-carrying capacity current-limiting fuse having a voltage rating of 600 to 1000 volts comprising a casing, a pulverulent arc-extinguishing filler within said casing, a fuse link within said casing inter-connecting said terminal elements and being surrounded by said filler, said fuse link comprising a plurality of portions of minimum cross-section, a plurality of portions of maximum cross-section and a plurality of intermediate portions of progressively changing cross-section, said plurality of portions of minimum cross-section portions and said plurality of progressively changing cross-section portions forming a plurality of serially related pairs of parallel current paths, the sum total of the length of said plurality of minimum cross-section portions being but a small fraction of the sum total of the length of said plurality of maximum cross-section portions and of the length of said plurality of progressively changing cross-section portions, the total length of said link being approximately two inches, and means for causing initial fusion of said link at a temperature lower than the fusing point of the metal of which said link is made, said initial fusion causing means being associated with only one of said plurality of pairs of parallel current paths to initiate fusion of said link at the point thereof

where said one of said plurality of pairs of parallel current paths is located.

32. In combination an electric circuit, a current-limiting fuse arranged in said circuit, said fuse comprising a casing, terminal elements on opposite ends of said casing, a fuse link interconnecting said terminal elements and having a plurality of spaced portions of minimum cross-section, a plurality of spaced portions of maximum cross-section, and a plurality of intermediate portions of varying cross-section, each said minimum cross-section portions having a sufficiently small cross-sectional area to initiate arcing at instantaneous currents far below the available short-circuit current of said circuit and being constituted by a pair of conductive elements forming separate parallel current paths, the sum total of the length of said plurality of maximum cross-section portions and of the length of said plurality of intermediate cross-section portions being a multiple of the sum total of the length of said plurality of minimum cross-section portions, means associated with only one of said plurality of minimum cross-section portions for causing initial fusing of said link at protracted small overloads at a lower temperature than the fusing point of the metal of which said link is made, a pulverulent arc-extinguishing filler within said casing surrounding said link, said filler having a sufficiently high arc-extinguishing capacity in relation to the arcs initiated at said portions of minimum cross-section at fault currents of short-circuit current proportions to effect permanent interruption of any short-circuit current that said circuit is capable of producing in less than $\frac{1}{120}$ of a second after the time of fault inception, the sum total of the length of said plurality of minimum cross-section portions, said plurality of maximum cross-section portions and said plurality of intermediate portions exceeding the length of said link vaporized under the most onerous circuit interrupting conditions to which said fuse may be subjected in said circuit.

33. In combination an electric circuit, a current-limiting fuse arranged in said circuit, said fuse comprising a casing, terminal elements on opposite ends of said casing, a fuse link of silver interconnecting said terminal elements and having a plurality of substantially equidistant circular perforations arranged along the center line thereof, said perforations extending along a predominant portion of the length of said link and establishing a plurality of serially related pairs of parallel current paths, each said pairs of parallel current paths having a cross-sectional area sufficiently small to cause arc initiation at instantaneous currents far below the available short-circuit current of said circuit, alloy-forming means associated with one of said pairs of parallel current paths for lowering the fusing point of said link at the point where said one of said pairs of parallel current paths is located, a pulverulent quartz filler within said casing surrounding a sufficient portion of the total length of said link to cause arcs initiated substantially simultaneously at the occurrence of fault-currents of short-circuit current proportions at said plurality of serially related pairs of current paths to be permanently extinguished in less than $\frac{1}{120}$ of a second after fault inception, the sum total of the perforated and non-perforated portions of said link exceeding the length vaporized under the most onerous circuit interrupting conditions to

which said fuse may be subjected in said circuit to leave some residual non-vaporized link metal within said casing even on the occurrence of said most onerous circuit interrupting conditions.

34. A current-limiting low-voltage fuse comprising a pair of terminals, a ribbon-type multi-perforated fuse link connected to and extending between said pair of terminals, a pulverulent fulgurite-forming arc-quenching substance surrounding said link, and a casing substantially of an organic material housing said link and said substance, the distance between said link and the internal wall of said casing being approximately equal to the radius of the fulgurite formed by said substance upon blowing of the fuse.

35. In a current-limiting low-voltage fuse of the type wherein one single fuse link is arranged in a casing, the combination of a pair of terminals, a ribbon-type fuse link connected to and extending between said pair of terminals, said link having a plurality of portions of relatively small width spaced substantially equidistantly and arranged substantially along the entire length of said link and a plurality of portions of relatively larger width intermediate said small width portions, each of said relatively larger width portions having a length being a multiple of the length of one of said small width portions, a pulverulent fulgurite-forming arc-quenching filler surrounding said link, a casing substantially of an organic material housing said link and said filler, and the internal diameter of said casing being approximately equal to the diameter of the fulgurite formed by said filler upon blowing of the fuse.

36. A current-limiting fuse having a voltage rating of 600 to 1000 volts, comprising a pair of terminal elements, a ribbon-type fuse link of silver connected to and extending between said pair of elements, said link comprising a plurality of portions of minimum width, a plurality of portions of maximum width, and a plurality of intermediate portions of progressively changing width, said plurality of portions of minimum width being spaced substantially equidistantly and arranged along a preponderant portion of the length of said link, said plurality of portions of minimum width and said plurality of progressively changing width portions forming a plurality of serially related pairs of parallel current paths, the sum total of the length of said plurality of minimum width portions being but a small fraction of the sum total of the length of said plurality of maximum width portions and the length of said plurality of progressively changing width portions, a quartz filler surrounding said link, a casing substantially of organic insulating material housing said link and said quartz filler, and the distance between said link and the internal wall of said casing being approximately equal to the radius of the fulgurite formed by said filler on occurrence of a short-circuit current.

37. A current-limiting fuse having a voltage rating of 600 to 1000 volts comprising a pair of terminal caps, a ribbon-type fuse link conductively connected to and extending between said pair of caps, said link having a plurality of substantially equidistant perforations aligned along the longitudinal axis of said link and arranged along a preponderant portion of the length thereof, a body of quartz sand surrounding said link, and a tubular casing having a coaxial external and internal surface, said internal surface being of an organic insulating material, said casing support-

ing said caps and housing said link and said body of quartz sand, the internal diameter of said housing being in the order of the spacing between said perforations and not substantially exceeding said spacing.

38. A current-limiting low-voltage fuse of the type wherein one single fuse link is arranged in a tubular insulating element, comprising a pair of terminal caps, a ribbon-type fuse link conductively connected to and extending between said pair of caps, said link having a plurality of circular substantially equidistant perforations aligned along the longitudinal axis thereof and arranged along a preponderant portion of the length thereof, a fusing-point-reducing metal element associated with one of said perforations, a body of quartz sand surrounding said link to form a fulgurite upon vaporization thereof, and a tubular insulating element supporting said caps and having an external diameter substantially equal to the internal diameter of said caps, said tubular element housing said link and said body of quartz sand and having an internal wall consisting of an organic insulating material, the average spacing between said link and said internal wall being approximately equal to the maximum transversal growth of said fulgurite resulting in maximum transversal growth of said fulgurite to immediately adjacent said internal wall.

39. A current-limiting low-voltage fuse comprising a pair of spaced terminal caps, a body of quartz sand, a ribbon-type fuse link conductively connected to and extending between said pair of caps and embedded into said body of quartz sand, said link having a plurality of substantially equidistant perforations aligned along the longitudinal axis thereof and arranged along a preponderant portion of the length thereof to form a plurality of serially related pairs of parallel current paths, the spacing between each of said plurality of perforations being sufficiently large to preclude merger of the serially related pairs of parallel arclets formed at said pairs of parallel current paths on interruption of short-circuit currents into longer arcs, and a tubular insulating element for housing said body of quartz sand and said link and for supporting said caps on the outer surface thereof, the inner surface of said insulating element consisting of an organic insulating material.

40. A current-limiting low-voltage fuse comprising a pair of spaced terminal caps, a body of quartz sand, a ribbon-type fuse link conductively connected to and extending between said pair of caps, and embedded in said body of quartz sand, said link having a plurality of relatively short substantially equidistantly spaced portions of restricted width arranged along substantially the entire length thereof and a plurality of intermediate portions of greatly increased width and of sufficient length to preclude merger of the serially related arclets formed at said restricted width portions on interruption of short-circuit currents into one single long arc, and a tubular element of insulating material for housing said body of quartz sand and said link and for supporting said caps on the external surface thereof, said tubular housing being of an organic nature at the internal surface thereof.

41. In combination, an electric circuit having a circuit voltage not exceeding 1000 volts, a current-limiting fuse arranged in said circuit, said fuse comprising a casing consisting substantially

of an organic insulating material, a pulverulent arc-quenching filler in said casing, terminal elements on opposite ends of said casing, a ribbon-type fuse link conductively interconnecting said elements and surrounded by said filler, said links having a plurality of substantially equidistantly spaced perforations positioned along the longitudinal axis thereof and provided along a preponderant portion of the length thereof to form a plurality of serially related pairs of parallel current paths, said pairs of parallel current paths having a sufficiently small cross-sectional area to cause initiation of serially related pairs of parallel arclets at the occurrence of a short-circuit current in said circuit before said current can rise to the peak value thereof, and the spacing between said plurality of perforations being sufficiently large to preclude a merger of said serially related pairs of parallel arclets into one single long arc.

42. In combination, an electric circuit having a circuit voltage not exceeding 1000 volts, a current-limiting fuse arranged in said circuit, said fuse comprising an insulating casing, terminal elements on opposite ends of said casing, a ribbon-type fuse link interconnecting said terminal elements and having a plurality of portions of reduced width spaced substantially equidistantly along a preponderant portion of the length of said link and a plurality of portions of relatively larger width intermediate said reduced width portions, each of said plurality of reduced width portions having a sufficiently small cross-sectional area to initiate arcing at the occurrence of a short-circuit current in said circuit before said current can rise to peak value thereof, each of said plurality of relatively larger width portions having a length being a multiple of the length of said reduced width portions, a body of quartz sand surrounding said link, the number of said reduced width portions being sufficiently large and the length of said larger width portions sufficiently high in relation to the arc-quenching-capacity of said body of quartz sand to effect extinction of the serially related arclets formed at said reduced width portions at the occurrence of a short-circuit current in said circuit before said arclets can merge into one single long arc, the mass of said link being so small as to limit the peak of the let-through current of said fuse to sufficiently low values to enable said body of quartz sand to effect extinction of said arclets in 1 to 1.5 times the time elapsing between initiation of a short-circuit in said circuit and initiation of said arclets, even if said short-circuit is initiated at such a lead angle that initiation of said arclets occurs within the range of 20 degrees prior and 10 degrees after the peak of the circuit voltage.
